JAY A. MACKEY, OF LYNN, MASSACHUSETTS, ASSIGNOR TO THE SINGER MANUFACTURING COMPANY, OF ELIZABETHPORT, NEW JERSEY, A CORPORATION OF NEW JERSEY.

PERFORATING-MACHINE.

1,329,788.

Specification of Letters Patent.

Patented Feb. 3, 1920.

Application filed February 23, 1917. Serial No. 150,458.

To all whom it may concern:

Be it known that I, JAY A. MACKEY, a citizen of the United States, and resident of Lynn, county of Essex, Commonwealth of Massachusetts, have invented an Improvement in Perforating-Machines, of which the following description, in connection with the accompanying drawings, is a specification, like characters on the drawings representing like parts in each of the several views.

This invention relates to machines for operating on sheet or strip material at spaced apart intervals and with a feed movement of the material, and more particularly to a machine for performing a perforating, or more or less analogous operation on the material at spaced apart intervals. While having other and more general fields of usefulness the invention is well adapted and designed for punching holes automatically at spaced intervals in leather, fabric or other relatively thin material. A prime object of the invention is to provide improved mechanism whereby the operating tool, such as a perforating punch, may be kept in continuous operative relation with a driving mechanism so as to be continuously driven with an elimination of disconnecting clutch devices, and with provision whereby the perforating punch or other tool may be moved at will into and out of operating position without disturbing its operating connection with its driving mechanism; *i. e.*, the range of movement of the tool is shiftable at will from an operating position where it coöperates with a suitable punch block or other backing, and with a feed for the material, to an inoperative position where it does not engage the material in its range of movement. A further important object is to provide a machine equipped with a shiftably mounted continuously driven tool and in combination therewith a feed mechanism for the material shiftable into and out of operating position simultaneously with the shifting of the tool into and out of its operating position, and preferably by the same operating means. A still further object is to provide improved operating means for a punch or like tool including a continuously engaged operating connection with a driving mechanism and having a manually shiftable member operable by the hand or a foot treadle adapted to move the punch into and out of its oper-

ating range at will. The foregoing and other objects and advantages of the invention will more fully appear from the following detailed description, and the distinctive features of novelty will be pointed out in the appended claims.

Referring to the drawings:

Figure 1 is a side elevation of a machine embodying the features of my invention;

Fig. 2 is a front elevation thereof with parts broken away;

Fig. 3 is a transverse vertical section on line 3—3 of Fig. 1;

Fig. 4 is a horizontal section on line 4—4 of Fig. 1;

Fig. 5 is a vertical detail section showing the shiftable driving connection to the punch plunger;

Fig. 6 is a sectional detail on line 6—6 of Fig. 5; and

Fig. 7 is a detail elevation showing the elements of the driving connection between the drive shaft and the punch.

The frame 1 of the machine has a horizontally extending portion 2 constituting a housing and mounting for the feed mechanism, and equipped with a table 3 constituting a material support over which the sheet or strip being operated on is fed. The frame is also formed with an upright portion 4 equipped with spaced apart horizontal bearings 5, 6 in which is journaled a driving shaft 7 suitably driven as by pulleys 8 at one end thereof. The frame upright 4 is also equipped with a horizontally extending portion formed with bearings 9 spaced above the table 3 in which is slidably fitted a punch plunger 10. This plunger is equipped with a suitable perforating punch 11 at its lower end, such punch typifying in a broader aspect any suitable operating tool. As shown, a suitable punch block 12 is fitted in the base extension 2 for coöperation with this punch when it is lowered to operative position, as now to be described. At its upper end the plunger 10 has pivotally engaged therewith at 13 a pitman 14, the other end of which is engaged with a crank pin 15 integral with or rigidly fixed to a crank pin bearing member shown as a block 16, the body of which is cylindrical, or circular in cross-section and rotatably fitted in a sleeve 17 formed at one end of a bar 18, the other end of which is pivotally

mounted on a lug of the frame work at 19. The swinging outer end of the bar 18 with its bearing sleeve 17 is drawn yieldingly upward by a spring 20 anchored to the frame work, so that it is held constantly in engagement with the projecting end of an operating lever 21 by which it may be pressed downward at will as presently explained. The block 16 is thus shiftable laterally upward and downward as shown with reference to the driving shaft 7, as the swinging bar 18 is acted on by the lever 21. A continuous driving connection from the shaft 7 to the crank pin bearing member or block 16 is preserved throughout such lateral shifting by means of an intermediate block or member 22 having one of its faces in slidable keyed engagement with the end of the shaft 7 as indicated at 23 and its other face with a slidable keyed engagement 24 with the crank pin bearing member or block 16, the key connections 23, 24 extending in directions at right angles to each other. Thus the intermediate block or member 22 is guided for straight line movement both with respect to the shaft 7 and with respect to the crank pin bearing member 16, and so the crank pin bearing member 16 along with the crank and tool connected therewith may be shifted vertically with a straight line movement which will bring the crank pin bearing member or block 16 into more or less offset relation with respect to the shaft 7 while preserving undisturbed the driving relation, this being allowed for by the vertical components of sliding movement in the sliding key connections 23, 24 when each of these is in other than its horizontal position, it being noted that when either of said key connections is in its horizontal position the other thereof is straight vertical. The intermediate block 22 thus constitutes a floating connection between the driving shaft 7 and the crank pin bearing member 16. It will be understood that while the key or spline connections 23, 24 are herein shown as formed with the rib member of such connection on the intermediate block 22 at each side thereof, this is merely illustrative and the groove might instead, at either or both sides, be formed in the block 22 with the mating rib on the coöperating member. It will be noted that the end of the bearing 6 adjacent the shiftable block 16 is formed with an enlarged annular recess 25 permitting the requisite range of shifting to the intermediate block 22 as the block 16 is raised and lowered for the adjustment of the tool as described. Thus for a punch or any more or less similar reciprocating tool, a continuous driving connection is provided, permitting a shifting of the tool through a range sufficient to bring it into operating position, or out of operating relation to the material.

My invention in its more comprehensive form includes in combination with a shiftable mounted continuously operated tool of the character described, a feeding device connected and arranged to be simultaneously moved into and out of material engaging position in synchronism with the movements of the tool. As herein shown the feed mechanism consists in a feed bar 26 equipped with a usual serrated feeding surface 27 at 75 its top, this bar being adjustably fixed as indicated at 28 on the end of a rock shaft 29 for a so-called "four-motion" feed movement which may be of usual known type, except for the special provision connecting it 80 with the shiftable tool as presently described. The rock shaft 29 is oscillated to swing the feed bar to and fro in usual manner by an upstanding arm 30 fixed thereto having at its end a bearing head 31 operating in the 85 lower end of a slotted bar 32 which pivots on a fulcrum block 33 on which it is slidable, the upper end of this bar being pivoted at 34 to a lever fulcrumed at 35 in the frame work and having a forked upper end 36 engaging an eccentric on the shaft 7. The fulcrum block 33 may be mounted in usual manner on a bracket member 37 adjustable on a vertical bar 38, and capable of being set in adjusted position by a clamp screw 95 39. The bar 38 is normally held yieldingly in an intermediate position by springs 40 reacting between abutments on the frame and heads 41 on said bar, the fulcrum block 33 being thus yieldingly held in a position to 100 effect normal feeding strokes of the feed bar. The bar 38 may be shifted to vary the position of the fulcrum 33 and hence the length of the feed strokes by a rock shaft 42 having a lever arm 43 fixed thereto and carrying a pin engaging a yoke member 44 projecting laterally from said bar, the shaft 42 being operable by an arm 45 projecting at the end of the machine for convenient manual operation by treadle or by hand, all 110 as is usual in this general type of machine. For moving the feed bar upward to material engaging position at the beginning of a feed stroke, and downward to disengage the material at the end of a feed stroke, a bar 45 115 is pivoted at 46 to an outer projection of a floating frame 47 in which the shaft 29 is journaled, this floating frame being pivoted to the shaft 42. The bar 45 is in two parts pivoted together at 45^a and having its upper 120 part laterally offset as indicated at 48 with the extremity thereof pivoted at 49 to a bell crank lever 50, the upper end of which is forked to engage an eccentric on the shaft 7. It will be observed that by reason of the lateral offset 48 at the top of the bar 45, the total length of the bar, *i.e.*, the distance between the pivot points 46 and 49 will be increased as the bar is broken at 45^a from the straight alignment as seen in Fig. 3, be- 130

cause the pivot point 45^a will then move more nearly into alinement with the end pivots 46 and 49. A spring 51 engages the bar 45 adjacent the pivot 45^a tending to normally move the two parts of bar 45 about the pivot 45^a so as to break said bar, *i. e.*, to lengthen its total extent, and thus rock the floating frame 47 downward which depresses the feed bar 26 out of operative position. The 10 bar 45 is provided adjacent the pivot 45^a with a cam surface 52 engageable by a projection 53 laterally extending from the end of one arm 54 of a bell crank lever which is pivoted at 55 on the frame and has its other 15 arm 56 extending upward with a link 57 pivoted at its upper end, the other end of said link being pivoted to an arm 58 which constitutes the other end of a lever whose arm 21 has already been described, said lever 20 having an intermediate fulcrum 59 at the top of the frame. The lever arm 54 may be operated from a depending bar 60 pivoted thereto, at the lower end of which a suitable treadle may be fixed, a suitable spring 61 25 being interposed to act on said bar for normally lifting it and the lever arm 54 to an upper limit of movement. The lever arm 56 and the link 57 constitute a toggle which when straightened as shown in Fig. 1, will 30 swing the lever arm 21 downward and thus move the tool plunger 10 and the punch 11 down to operating position, *i. e.*, so that at the lower limit of movement of the punch 11 it coöperates with the punch block 12, 35 while when the lever arm 54 is swung upward, the toggle 56, 57 is broken and the punch withdrawn from operating position, though continuing its vibrating movement as described. It may thus be understood 40 that as the lever arm 54 is swung upward, and the punch 11 thus raised out of operating position, the feed bar 26 is at the same time depressed below its operating position by the projection 53 moving off the cam 52 45 and thus permitting the pivot 45^a to swing outward under the action of the spring 51 to lengthen the bar 45 and thus swing the floating frame 47 of the oscillating feed shaft 29 downward, while upon a depression of the 50 arm 54 by the treadle, at the same time that the punch is moved downward to operative position by the straightening of the toggle 56, 57 the feed bar 26 is moved up to material engaging position by the moving inward 55 ward of the pivot 45^a on the engagement of the projection 53 with the cam 52.

In use it will be understood that the spring 61 or equivalent means acting on the treadle bar 60 will hold the lever arm 54 elevated, this through the other arm 56 of the bell crank lever 54-56 swinging the lower end of the link 57 inward from the position shown in Fig. 1 and thus swinging upward the outer end of the lever 21 to 60 hold the punch plunger elevated, *i. e.*, with

its range of movement out of operative position. At the same time the projection 53 on the outer end of the arm 54 is held raised above and off of the cam 52, thus permitting the spring 51 to shift the pivot 47 to the left 70 from the position shown in Fig. 3, *i. e.*, more nearly into alinement with the pivots 46, 49, thus swinging downward the rock shaft 29 and with it the feed bar to hold it for an inoperative range of movement. Upon depressing the treadle the parts are moved to the position shown in the drawings wherein the toggle formed by the lever arms 56, 57 is straightened and the punch plunger thus moved down to operative position, while at 80 the same time the projection 53 moving down to engage the cam 52 moves the pivot 47 in the bar 45 to the position shown, *i. e.*, farther from alinement with the pivots 46, 49 and thus swings the shaft 29 and the feed 85 bar up into operative position; the feed bar and punch plunger thus remaining coöperative in operative position so long as the treadle is held depressed but being both returned simultaneously and automatically to 90 inoperative position as soon as the treadle is released,—the operative condition of the machine being thus under full control of the operator by simple manipulation of a single treadle.

The machine is shown as equipped with a usual roller presser foot 62 carried at the lower end of a presser bar 63 slidably mounted in the frame and yieldingly pressed downward by a spring 64, this presser foot 100 having a usual cam device 65 for lifting it operable by a lever 66, these forming no part of the present invention. A suitable mounting for the intermediate portion of the shaft 42 is provided by a block 67 providing at its ends spaced apart bearings for said shaft and itself having a stout lateral stud 68 extending into, and fixed in, a socket in the frame as indicated at 69, a suitable clamp screw 70 being provided for 110 removably fixing this stud and the block 67 in place. It will be understood that the described mechanism while well adapted, and especially designed, for use in a perforating machine employing a perforating 115 punch, is in a broader aspect and as to most of its essential features, likewise adapted for other machines employing a reciprocating tool and wherein the material is fed step-by-step to space the punching or other 120 operations thereon. I am aware that the invention and its respective features may be embodied in other specific forms without departing from the spirit or essential attributes thereof and I therefore desire the present embodiment to be considered as illustrative and not restrictive, reference being had to the appended claims rather than to the foregoing description to indicate the 125 scope of the invention.

Having described my invention, what I claim as new and desire to secure by Letters Patent is:

1. A machine of the kind described comprising a perforating tool mounted for vibration and also for bodily endwise shifting to and away from an operative position, a relatively fixed backing block coöoperative with said tool in its operative position, and 10 rotary driving means for said tool, said rotary driving means including a drive shaft, and an element slidably shiftable by a straight line movement with respect thereto with connections to shift the tool there- 15 with and equipped to transmit the rotary movement of the shaft as a vibrating tool movement throughout the shifting range thereof.
2. A machine of the kind described, comprising a perforating tool, means for mounting said tool for vibration and also for bodily endwise shifting to and away from an operative position, a relatively fixed backing block coöoperative with said tool in 25 its operative position, and rotary driving means for said tool, said rotary driving means consisting in a drive shaft, an intermediate element keyed to the end thereof for limited transverse sliding movement, a 30 crank-pin-bearing member slidably keyed to said intermediate element for sliding at an angle with reference to the keyed connection thereof with said shaft, and manually controlled means for adjusting said crank- 35 pin-bearing member transversely with respect to said shaft.
3. A machine of the kind described, comprising a tool, means for mounting said tool for vibratory operative movement and also 40 for bodily shifting into and away from an operative position, rotary driving means for said tool consisting in a drive shaft, an intermediate element keyed thereto for limited transverse sliding movement, a member 45 equipped for imparting vibration to said tool slidably keyed to said intermediate element for sliding at an angle with reference to the keyed connection thereof with said shaft, and manually controlled means for 50 adjusting said vibration imparting member transversely with respect to said shaft.
4. A machine of the kind described, comprising a perforating tool mounted for vibration and also for bodily endwise shifting 55 to and away from an operative position, a relatively fixed backing block coöoperative with said tool in its operative position, and rotary driving means for said tool, said rotary driving means consisting in a drive 60 shaft, an intermediate element keyed to the end thereof for limited transverse sliding movement, a crank-pin-bearing member slidably keyed to said intermediate element for sliding at an angle with reference to the

keyed connection thereof with said shaft, 65 and a treadle operated sleeve in which said crank pin bearing member has bearing, for shifting said member and the tool operated thereby into and out of operative position.

5. A machine of the kind described, comprising a vibrating tool mounted for bodily shifting movement into and out of an operative position, means for vibrating said tool, and means for feeding material step-by-step to be operated on by said tool, said feeding 75 means having connections constructed and arranged to shift the same to inoperative position as the tool is shifted to inoperative position, and for shifting the feeding means to operative position as the tool is shifted 80 to operative position.

6. A machine of the kind described, comprising a tool mounted and equipped with means for vibrating it and also for shifting it bodily into and out of operative position 85 while preserving its connections for continuous vibration, feeding means for material coöoperative with said tool, mounted and connected for vibrating movement and also for bodily shifting into and out of operative 90 position, and means connecting said tool with said feeding means for simultaneous shifting of both, whereby the tool and feeding means are each shifted into and out of operative position with respect to the material operated on, in synchronism.

7. A machine of the kind described, comprising a tool mounted and connected for vibrating operative movement and also for bodily shifting into and out of operative 100 position while preserving its connections for vibrating, a "four-motion" feed mechanism connected for vibrating movement in timed relation to the vibrations of said tool, said feed mechanism having a mounting for 105 bodily shifting into and out of operative position, and connections between said tool and said feed mechanism for shifting said feed mechanism backward out of operative 110 position, as the tool is shifted out of operative position, and for shifting the feed mechanism forward into operative position as the tool is shifted into operative position.

8. A machine of the kind described, comprising a perforating punch mounted for 115 vibration and also for bodily movement into and out of operative position while preserving its connections for vibration, a relatively stationary punch block coöoperative with said punch in its operative 120 position, a "four-motion" feed mechanism mounted and connected for vibration in timed relation with the vibration of said tool, and a single manually operated mechanism connected to the mounting of said 125 feed mechanism and also to said tool for shifting said tool and said feed mechanism into and out of their respective operative

positions simultaneously, while preserving continuous driving connections to both.

9. A machine of the kind described, comprising a tool, means for mounting said tool for vibratory operative movement and also for bodily shifting into and away from an operative position, rotary driving means for said tool consisting in a drive shaft, an intermediate element keyed thereto for limited transverse sliding movement, a member equipped for imparting vibration to said tool slidably keyed to said intermediate element for sliding at an angle with reference to the keyed connection thereof with said

shaft, means for adjusting said vibration 15 imparting member transversely with respect to said shaft, and means for feeding material step-by-step to be operated on by said tool, said feeding means having connections constructed and arranged to shift 20 the same to inoperative position as the tool is shifted to inoperative position and for shifting the feeding means to operative position as the tool is shifted to operative position. 25

In testimony whereof I have signed my name to this specification.

JAY A. MACKEY.
